ATTORNEYS

UNITED STATES PATENT OFFICE.

DENNIS McNEILL, OF HUNTINGTON, WEST VIRGINIA.

HINGE.

Application filed December 6, 1921. Serial No. 520,408.

To all whom it may concern:

Be it known that I, DENNIS McNEILL, a citizen of the United States, and a resident of Huntington, in the county of Cabell and 5 State of West Virginia, have invented a new and Improved Hinge, of which the following is a full, clear, and exact description.

This invention relates to improvements in hinges, an object of the invention being to 10 provide an improved construction of hinge pin having a longitudinal lubricant containing groove therein which serves to lubricate all movable parts of the hinge and can be readily removed, cleaned and refilled from 15 time to time as may be desired.

A further object is to provide a hinge having an improved construction of hinge pin which can be manufactured and sold at a cost the same as the ordinary hinge pin 20 as it can be formed in the die in like manner with the ordinary structure, and yet which will provide means whereby a lubricant can be maintained in proper relation to the movable sleeves or elements in the hinge to 25 lengthen the life of the hinge and prevent noise by operation thereof.

With these and other objects in view the invention consists in certain novel features of construction, and combinations and arrangements of parts as will be more fully 30 hereinafter described and pointed out in the claims.

In the accompanying drawings—

Figure 1 is a view mainly in front elevation, but showing in longitudinal section the hinge knuckles and the hinge pin in elevation thereon.

Figure 2 is a view in section on the line 2—2 of Figure 1.

40 1 and 2 represents the leaves of an ordinary separable hinge and 3 is the aligned sleeves or hinge knuckles which receive my improved hinge pin 4. This hinge pin 4 is removable as is customary, and is provided 45 preferably with a knob 5 at one end corresponding with the fixed knob 6 on one of the leaves of the hinge.

It is, of course, obvious that the exact shape of the pin head or other form of head 50 is immaterial, but it is, of course, necessary

to have some form of head to limit the movement of the pin and to facilitate its removal.

My improved hinge pin is made with a longitudinal groove 7 extending throughout its length, or at least throughout that portion of its length which acts as a pintle within the sleeves or knuckles 3 of the hinge. This groove 7 is filled with a lubricating composition 8 which is of sufficient consistency to remain in the groove and yet lubricate the surfaces and supply lubricant for an indefinite length of time. The invention is, of course, not limited to the particular lubricating means employed in the groove as 65 it is obvious that this is subject to modification, but my invention resides in the provision of a longitudinal groove in a hinge pin adapted to contain lubricating means which supplies the surfaces adjacent thereto. 70

I am, of course, aware that lubricating grooves in various articles are old, but the provision of a lubricant containing longitudinal groove in a hinge pin is an absolutely new idea so far as I have any knowledge and in the provision of such a construction of pin I am enabled to use the same as any ordinary pin or replace ordinary pins and provide a lubricant containing pin which supplies the lubricant as it is needed, and, 80 furthermore, can produce such a lubricating hinge pin that its cost is no greater than the cost of the ordinary pin.

Various slight changes might be made in the general form and arrangement of the 85 parts described without departing from the invention, and hence I do not limit myself to the precise details set forth, but consider myself at liberty to make such changes and alterations as fairly fall within the spirit 90 and scope of the appended claim.

I claim:

As a new article of manufacture, a hinge pin, a head on the hinge pin, and said pin having in its outer face and throughout its 95 length a straight longitudinal lubricant receiving groove, said head operating as a closure for the upper end of the groove when the pin is in position in a hinge.

DENNIS McNEILL.
